United States Patent Office.

AARON McNEILL, OF CINCINNATI, OHIO

Letters Patent No. 77,068, dated April 21, 1868.

IMPROVEMENT IN SAFETY-ATTACHMENT FOR POCKET-BOOKS.

The Schedule referred to in these Letters Patent and making part of the same.

TO ALL WHOM IT MAY CONCERN:

Be it known that I, AARON McNEILL, of Cincinnati, in the county of Hamilton, and State of Ohio, have invented a new and useful Safety-Attachment for Pocket-Books, &c.; and I do hereby declare the following to be a full, clear, and exact description of the same, reference being had to the accompanying drawing which forms part of this specification.

My invention consists of a chain or strap, secured to the bottom of the pocket by a button or other suitable means, and provided at its loose end with a spring-catch, which engages with a socket attached to the article to be secured for the purpose of preventing its abstraction without the owner's knowledge. In the drawings—

Figure 1 is a sectional view of the socket, catch, and a part of its attaching-chain.

Figure 2 is a view of the complete device, attached to a pocket-book.

A B may represent a metallic socket, which is attached to the pocket-book F, or other article to be secured, by rivets or other suitable means. C is a spring-catch, which is attached by a chain, D, and strap, E, to the bottom of the wearer's pocket. Said catch being forced into the contracted opening, b, of the socket, B, connects the article, to which said socket is attached, to the pocket, and thus prevents its abstraction without the owner's knowledge. The strap, E, is provided with a button-hole, which is passed over a button or hook, strongly fastened at or near the bottom of the pocket. The catch C corresponds in size with the interior of the socket b, and is of sufficient stiffness to require a moderate pressure to release it. It is detached from the socket by pressing and slightly pushing it with the finger. A strap or strong elastic cord may be substituted for the chain when desired.

Having thus described my invention, what I claim as new therein, and desire to secure by Letters Patent, is—

The flat spring-catch C, in combination with the socket A B b, and ligament D E, all constructed as herein represented and described, to prevent the abstraction of the pocket-book without the knowledge of the owner, but permit him to readily detach it within the pocket when desired.

AARON McNEILL.
